UNITED STATES PATENT OFFICE.

GEORGE RUBIN, OF CHICAGO, ILLINOIS.

PROTECTIVE CONTAINER FOR BOTTLES.

1,182,042.

Specification of Letters Patent.

Patented May 9, 1916.

Application filed September 10, 1914. Serial No. 861,023.

To all whom it may concern:

Be it known that I, GEORGE RUBIN, a citizen of the United States, and a resident of Chicago, in the county of Cook and State 5 of Illinois, have invented certain new and useful Improvements in Protective Containers for Bottles, of which the following is a specification.

My invention relates to a protective container for bottles, particularly for nursing bottles.

Nursing bottles now in use are usually of elongated cylindrical form with a nipple applied directly over the mouth thereof. 15 With this shape and arrangement it is necessary to either hold the bottle, or to prop it up in order that the contents will flow therefrom and the bottle will be prevented from slipping away from the child. Furthermore, the bottle being of glass it will 20 readily break and might seriously injure the child. Most important of all, however, is the maintaining of the bottle contents at a safe temperature.

25 The important objects of my invention are therefore to provide a protecting container for a nursing bottle which will maintain the temperature of the contents, and which will properly support the bottle for 30 proper nursing and which will prevent breakage of the bottle or injury to the child.

Another object is to provide a container which can be readily removed from the bottle and which when not in use can be folded into a minimum space.

My invention is preferably in the form of a double-walled bag preferably of flexible material such as rubber, which bag may 40 be filled either with liquid or with air and which, when so filled, will snugly surround the inserted bottle to protect it and to maintain the temperature of its contents for a long time.

45 The invention is clearly illustrated on the accompanying drawing in which—

Figure 1 shows my improved protective container in vertical diametral section with a bottle inserted therein, Fig. 2 is a 50 reduced sectional view on plane 2—2, Fig. 1, and Fig. 3 is a view similar to Fig. 1 showing a modified form of container.

The nursing bottle shown is of the kind now in general use comprising a cylindric 55 body A and a neck B with the retaining

flange C for the rubber nipple D which is applied to the neck. The improved container is preferably of flexible material such as rubber and is in the form of a bag comprising a central wall E surrounding the 60 pocket F, and the outer wall G spaced away from the inner wall E to leave the annular chamber H. The inner wall E has substantially the same shape as the bottle to be received in order to snugly fit the bottle 65 when it is inserted in the pocket F. At the lower end of the bag is the opening I into pocket F and at the upper end is the opening J for the bottle neck. The material of the bag at the lower junctures of the walls 70 E and G is extended inwardly to form a retaining flange K for the bottle after insertion thereof, while at the top of the bag the material at the juncture of the walls is extended to form the retaining flange L. 75

As the upper end of the bottle body is usually more or less tapered, the bottle can be readily slipped upwardly into the bag through the opening I, the flange K readily deflecting and stretching to allow such insertion. After the bottle is fully inserted against the flange L the flange K can readily be withdrawn into normal position below the base of the bottle to lock the bottle in the bag. Either before or after insertion of the bottle the annular compartment H of the bag can be filled with either liquid 80 or air, a suitable valve controlled inlet M being provided. Usually water of the desired temperature is filled into the bag in 85 order to keep the contents of the bottle at the desired temperature until the bottle is empty. Also where the bottle is filled for future use the bag may be filled with hot water of a temperature such that the bottle 90 contents will be of the desired temperature when it is to be used. Of course, when the bottle is to be used immediately after filling merely filling the bag with air might be sufficient to maintain the temperature of the 95 bottle contents during nursing.

Not only will my improved container keep the temperature of the bottle contents but it will serve as a protector against breakage of the bottle and injury to the 105 child. Neither will the child be injured if the protected bottle should fall or roll against it. Another great advantage of the protector, which greatly enlarges the diameter of the outfit, is that no propping is 110

necessary to bring the bottle into proper position for nursing. The bag need not be entirely filled and will then lay securely where it is placed, much like a rubber hot water bottle. Instead of having the outer wall G of the container bulging as shown in Fig. 1, it could be straight as shown in Fig. 2, and instead of being of circular cross section as shown in Fig. 2, the outer wall 10 could be of elliptic form.

The container of my construction is sanitary and can be readily cleaned, and when empty it can be readily folded into a small space. Not only is my improved container 15 useful in connection with nursing bottles but it could be used in connection with other bottles.

I do not desire to be limited to the exact form, construction and use referred to as 20 modifications are no doubt possible which

would still come within the scope of the invention, and

I claim the following:

A flexible protective container for bottles comprising a tubular part open at both 25 ends but contracted thereat to form retaining flanges for a bottle, and an outer part surrounding said tubular part to form therewith an annular chamber for liquid or air, there being an unobstructed passage- 30 way through said tubular part when the bottle is removed.

In witness whereof, I have hereunto set my hand this 4th day of September, A. D., 1914.

GEORGE RUBIN.
